FRANK J. WHELAN, OF NEW YORK, N. Y., AND THOMAS FRANCIS DWYER, JR., OF CAMBRIDGE, MASSACHUSETTS, ASSIGNEES TO SUPERIOR ENGINEERING COMPANY, OF BOSTON, MASSACHUSETTS

SOOT BLOWER

Application filed August 13, 1926. Serial No. 128,978.

This invention relates to improvements in soot blowers designed to be permanently mounted on a locomotive and operative to free the flue sheet and flues from soot and other accumulations.

It has for its particular object the provision of a device that can be operated while the locomotive is under way and which can be controlled by the engineer from the cab.

10 To this end, in each water leg of the boiler is seated a stay tube extending transversely of the same and opening into the fire box in front of the flue sheet. In each of these stay tubes is mounted a casing containing the 15 operative parts of the device, including a rotatable nozzle provided with a valve-controlled connection with a suitable source of pressure fluid. Means operable from the cab are provided whereby the nozzle can be oscillated to sweep the pressure fluid projected therefrom across the flue sheet and the ends of the flues, the force of the pressure fluid, augmented by the draft of the furnace, operating to dislodge the soot and other accumulations from the flue sheet and flues so that the loosened material can be carried with the other products of combustion by the exhaust 25 to the stack.

In the drawings, which illustrate a preferred embodiment of the invention, and in which similar reference characters designate corresponding parts,

Figure 1 is a plan view of a boiler flue cleaner embodying the invention, parts being broken away. In this view a section of a water leg of a locomotive boiler is shown with a stay tube seated therein and the nozzle pipe of the cleaner projecting through the stay tube.

40 Figure 2 is a plan view of the flue cleaner, with parts broken away.

Fig. 3 is a longitudinal vertical section through the apparatus. Fig. 4 is a transverse section on the line 4-4 of Fig. 3. Fig. 5 is a 45 detail view, showing the conical gudgeon that forms one of the bearings for the nozzle pipe. Figs. 6-11 are enlarged detail views of the spraying nozzle. Fig. 6 is a longitudinal sectional view. Fig. 7 is an inner end elevation. Fig. 8 is a plan view. Figs. 9, 10 and

11 are sectional views on the lines 9-9, 10-10 and 11-11, respectively, of Fig. 6.

In practice two of the devices are employed, one in each side of the fire-box and operative to project the pressure fluid over 55 considerably more than one-half of the surface of the flue sheet so that the operation of both will cover the entire surface. As the two devices are alike in construction and operation, a description of one will suffice for 60 both.

Referring to the drawings in detail, 10 designates a water leg of the locomotive boiler on which the apparatus is mounted. Extending transversely across this water leg 65 is the stay tube 11 with its ends seated in the opposite walls of the leg. A main casing 12 is provided with a flat inner face to abut the outer wall of the water leg and is flanged, as at 13, to receive the bolts 14 that extend into 70 the outer wall of the water leg to hold the casing in place. On the inner side of the casing and central to the flat face thereof is a cylindrical nipple 15 fitting the stay tube 11. Surrounding this nipple is a packing 16 75 clamped by the bolts 14 between the face of the casing and the wall of the water leg to prevent leakage between the nipple and the stay tube. Leading upward through the casing is a passage 17 connected by the pipe 18 80 with a source of supply of pressure fluid (not shown), which may be the steam turret of the boiler so that the dry steam therefrom may be utilized for the cleansing purpose. The pipe 18 is controlled by a throttle valve 85 that may be controlled by an actuating rod (not shown) extending to a suitable control position, such as the cab of the locomotive.

A nozzle pipe 21 extends horizontally 90 through the lower part of the casing 12 across the passage 17 and in axial alinement with the stay tube 11 and the nipple 15. The nipple forms a bearing for the outer end of the nozzle pipe and the inner end of the pipe is journaled in the conical gudgeon block 22 95 seated in a conical opening in the wall of the casing, the base of the block facing inward so that the pressure fluid in the casing will be imposed on the block to force the latter into its conical seat and around the pipe and 100

thereby prevent leakage from the casing at that point. At an intermediate part of the nozzle pipe, in the wall thereof, is a port 23 to register with the passage 17 in the casing. On the inner wall of the casing and opposite to the intermediate part of the nozzle pipe is a curved seat 24 against which the pipe bears to effect an opening and closing of the port 23 as the pipe is turned.

10 On the outer end of the pipe 21 is secured the nozzle 25 partly within the stay tube and projecting from the latter into the fire-box in front of the flue sheet and to one side thereof, the axis of the nozzle being normal to the axis of the fire flue. The nozzle is provided with a slotted discharge orifice 26 angularly disposed to the axis of the nozzle, the shape of the orifice being such as to project the pressure fluid in a fan-like stream against 20 the flue sheet and the ends of the flues as the nozzle pipe is oscillated. The spraying effect of each nozzle covers considerable more than one-half of the area of the flue sheet, so that the combined spraying effect of the two opposite nozzles will cover the entire surface of 25 the flue sheet.

On the inner end of the nozzle pipe 21, which extends outside of the casing 12, is mounted the segmental gear 27, being secured thereon by the bolt 28 passing through its hub and the end of the pipe. With this segmental gear 27 meshes the worm shaft 29 journaled in bearings formed in the auxiliary housing 30 secured to the outer side of the casing 12 by the bolts 31 extending through the flange 13' (Fig. 1) on the outer side of the main casing 12 into the upper inner edge of the auxiliary casing and by the bolts 31' (Fig. 2) extending through the lower part 40 of the auxiliary casing into the main casing. As the worm-shaft is rotated back and forth by the crank 37 and the intervening mechanism, the segmental gear 27 is oscillated to impart a like movement to the nozzle pipe. 45 The limit of the turning movement of the crank in either direction can be determined by an indicator (not shown) of the type usually employed for such purposes. Longitudinal movement of the worm shaft 29 in its bearing is prevented by the nut 32 threaded on one end of the shaft and abutting the adjacent side of the housing; on the other end of the worm shaft is pinned the coupling member 33 abutting the housing on that side. 50 The nut 32 on one end of the shaft and the coupling member 33 on the other end of the shaft, with these two members bearing against the interposed housing, longitudinal movement of the worm shaft will be prevented. Another coupling member 34 is pinned to the operating rod 35 and the two members 33 and 34 are hinged together to 55 form a universal joint connecting the operating rod and the work shaft. The operating shaft is journaled in bearings carried by the

brackets 36 fastened to a suitable support, as the outer wall of the water leg 10 of the boiler. The operating rod or shaft leads to the engineer's station in the cab (not shown) and there it is provided with a crank 37 by means of which the operating rod can be rotated. The universal joint formed by the angularly hinged members 33 and 34 permit change in direction of the operating rod relatively to the worm shaft to accommodate the required 75 mounting.

The end of the nozzle pipe 21 extending into the housing 30 has a plug 39 inserted in the same to close the outward passage through the pipe. This plug also strengthens the end of the pipe and through the block extends the bolt 28 securing the worm gear 27 in place. The outer end 40 of the plug projects beyond the end of the nozzle pipe and is reduced in diameter. This reduced end 40 of the plug forms a journal that extends through a bearing in the housing 30 and on its extremity is threaded the nut 41. The wall of the housing, being engaged between the nut 41 and the shoulder of the plug 39, holds the nozzle pipe 21 against longitudinal movement in the casing. At the upper part of the auxiliary casing or housing 30 is a hood 50 projecting over the outer part of the segmental gear 27 to protect the same.

The detail construction of the spraying nozzle 25 is illustrated in Figs. 6-11. In practice this nozzle is made of a metal alloy that will withstand the heat and chemical action of the products of combustion in the fire-box. Such an alloy is one composed of 70 to 90 per cent of nickel and of 30 to 10 per cent of chromium. As the nozzle remains constantly in the fire-box, and is continuously subjected to the action of the heat and gases of combustion, the advantage of forming it of such a resisting alloy is obvious.

As the nozzle 25 is positioned to one side of the fire-box, its orifice 26 is a greater distance from the central part of the flue sheet than it is from the side of the flue sheet. Consequently the cleansing pressure fluid will be projected more directly and with greater force toward the side of the flue sheet and with a decreasing force toward the central part of the flue sheet owing to the increase in distance from the orifice of the nozzle. With the orifice of the same width throughout, the cleansing action would be uneven for it would be more effective at the side of the flue sheet than toward the central part thereof. To avoid this tendency, the orifice of the nozzle and the passages leading thereto are so shaped and proportioned as to project a greater volume of pressure fluid toward the central part of the flue sheet than toward the side thereof, so that the greater volume of pressure fluid striking with less force the central part of the flue sheet offsets the lesser volume of pressure fluid striking 130

the side of the flue sheet with greater force.

In the formation of the nozzle (Figs. 6-11), the opposite ends of the orifice 26 are struck on arcs of circles of different radii, as at 42 and 43, in which merge the sides 44 of the orifice, gradually approaching each other from the greater arcuate end of the orifice to the lesser arcuate end. The orifice end 45 of the nozzle is angularly disposed to the main part 46, the inner end wall 47 of the orifice being normal to the longitudinal axis of the main part, and the outer end wall 48 being inclined about thirty-five degrees from said axis. At the bend connecting the orifice end and main part of the nozzle is the restricted throat 49 (Fig. 9) of the same general outline as that of the orifice 26. From the throat to the edge of the orifice the arcuate parts 42 and 43 are divergently flared toward their outer ends (Fig. 6), but at their intermediate parts (Fig. 10) the sides are substantially parallel in their outward extension.

The passage so formed through the emission end of the nozzle projects the pressure fluid in a fan-like stream, that part emitted from arcuate end 42 of the orifice being directed toward the central part of the flue sheet and that part from the arcuate end 43 striking the side of the flue sheet, with the intermediate part of the fan-like stream covering the intermediate part of the flue sheet. As that part of the stream emitted from the arcuate end 42 has the greater distance to travel before it strikes the flue sheet it has less effective striking force than that part emitted from the arcuate end 43, which has a shorter distance to travel before it strikes the flue sheet, but the greater volume of the former offsets the greater striking force of the latter so that the cleaning effect is equalized over the entire surface of that part of the flue sheet covered by the fan-like stream. The restricted area of the throat and passage through the orifice end of the nozzle, as compared with the cross-area of the main part of the nozzle, effects a venturi action to increase the velocity of the emitted stream so that a more effective cleansing action is obtained. The inner end of the main part 46 of the nozzle is cylindrical and is threaded to engage the outer end of the nozzle pipe 21.

The operation of the apparatus is as follows: In the initial position of the operative parts of the apparatus, the port 23 in the nozzle pipe 21 abuts the curved seat 24 in the wall of the casing and communication between the passage 17 and the nozzle pipe is thereby closed. This closed position of the port 23 coincides with the checking of the segmental gear in its turning movement by the worm shaft in one direction. When it is desired to clear the flues and the flue sheet, the most advantageous time is when the locomotive is under way and the exhaust is at

full blast through the uptake of the furnace so that the maximum draft through the flues will be provided. Under these conditions the engineer opens the throttle valve 19 so that the pressure fluid can pass through the pipe 18 into the passage 17 of the casing 12. He then slowly turns the crank wheel 37 and through the intervening mechanism the nozzle pipe 21 is rotated until the segmental gear is checked in its turning movement in that direction. During this partial rotation of the nozzle pipe the port 23 leaves the curved seat 24 and communication is established between the passage 17 in the casing and the interior of the nozzle pipe. This communication is maintained until the nozzle pipe is turned back to its initial position.

In the initial position of the pipe 21, the discharge orifice 26 in the nozzle 25 is positioned to direct the pressure fluid against the upper part of the flue sheet. As the pipe is rotated the nozzle is turned so that the fan-like stream of pressure fluid sweeps the flue sheet from top to bottom and covers considerably more than a half of the surface on the side on which is mounted the apparatus being operated. The force of the projected pressure fluid combined with the maximum draft through the flues created by the exhaust from the engine dislodges the accumulations of soot and cinders from the flue sheet and flues and the dislodged material is carried by the draft with the other products of combustion to the uptake of the furnace. When the turning movement of the nozzle pipe reaches its limit in one direction, the engineer reverses the crank wheel and the nozzle pipe is returned to its initial position with the port 23 closed on its seat 24. In this return movement the pressure fluid jet sweeps the flue sheet from bottom to top. During the first part of the cleaning operation the discharge from the stack is noticeably black from the dislodged soot, but as the operation continues the discharge clears and by observing these conditions the engineer can determine when the operation is sufficient.

While the cleaning operation can be accomplished to the best advantage while the locomotive is under way, yet it can be done while the engine is standing, but under this condition the stack blower and superheater damper must be wide open.

What we claim is:

1. In a boiler flue cleaner, the combination of a main casing provided with an induction passage and having a cylindrical nipple on one side, with a pipe journaled in the casing and extending through the cylindrical nipple in axial alignment therewith and provided with a port to register with the induction passage, a nozzle on the end of the pipe extending outside of the nipple, a plug fixed in the other end of the pipe to close the same and provided at its outer end with a reduced

extension forming a journal in axial alinement with the pipe; an auxiliary housing detachably mounted on the outer side of the main casing to abut the closed end of the pipe and providing a bearing for the journal projecting from said end of the pipe, a gear fixed on the closed end of the pipe, a shaft journaled in the auxiliary housing and provided with a worm engaging the gear, and means for rotating, in either direction the shaft carrying the worm to move the gear back and forth to impart oscillatory movement to the pipe and the nozzle carried by said pipe.

2. In a boiler flue cleaner, the combination of a main casing provided with an induction passage and having a cylindrical nipple on one side, with a pipe journaled in the casing and extending through the cylindrical nipple in axial alinement therewith and provided with a port to register with the induction passage, a nozzle on the end of the pipe extending outside of the nipple, a plug fixed in the other end of the pipe to close the same and provided at its outer end with a reduced extension forming a journal in axial alinement with the pipe; a segmental gear fixed on the closed end of the pipe; an auxiliary housing detachably mounted on the outer side of the main casing to abut the closed end of the pipe and providing a bearing for the journal projecting from said end of the pipe, said auxiliary housing including a hood extending over the segmental gear, a shaft journaled in the auxiliary housing and provided with a worm engaging the segmental gear, and means for rotating in either direction the shaft carrying the worm to move the segmental gear back and forth to impart oscillatory movement to the pipe and the nozzle carried thereby.

3. In testimony whereof we affix our signatures.
